UNITED STATES PATENT OFFICE

2,446,339

SPEED DENSITY CARBURETOR

Andrew William Orr, Jr., Detroit, Mich., assignor
to George M. Holley and Earl Holley

Application February 9, 1946, Serial No. 646,559

5 Claims. (Cl. 123—119)

1

The object of this invention is to proportion the fuel to the air in an internal combustion engine. Specifically, the object is to control the fuel flow by: (a) the velocity of flow of the fuel to the engine; (b) the speed of the engine; (c) the density of the air entering the engine (MAP); (d) means responsive to the temperature of the charge to control the fuel; (e) means responsive to the back pressure of the exhaust to control the fuel; (f) to provide empirical means for controlling the low speed fuel flow.

Figure 1 shows the preferred form of my invention.

Figure 2 shows a partial cross-sectional elevation taken on plane 2—2 of Figure 1.

In Figures 1 and 2, 10 is the fuel entrance, 12 is an engine-driven shaft driving a pump 14 at engine speed or at some speed proportional to engine speed, 26 is the pump outlet. Projecting from the right hand end of the pump 14 is a shaft 16, which carries governor balls 18, which engage to the right with the thrust disc 20 and to the left with the corresponding curved disc 22. The disc 22 is perforated and is moved by the diaphragm 24. Fuel pressure in the outlet 26 is connected through the passage 28 so as to act on the diaphragm 24, which pushes the disc 22 to the right; centrifugal force pushes the disc 22 to the left and opposes the fuel pressure acting on the diaphragm 24. The pressure created by the pump 14 causes the diaphragm 24 to move to the right and allows fuel to escape from the passage 28 to the chamber 30. Pressure in the chamber 30 acts on the diaphragm 33 and causes the valve 34 to open, compressing spring 41 and allows fuel to return to the fuel entrance through the passage 36. The rear chamber 40, to the right of the diaphragm 33, is connected through the passage 42 to the fuel entrance 10.

A venturi 44 is located in the outlet 26 from the fuel pump 14. A diaphragm 46 forms the left-hand wall of the chamber 50, which communicates through the opening 48 with the throat of the venturi 44.

The chamber 54, located to the left of the diaphragm 46, communicates through the passage 52 with the fuel outlet 26. The diaphragm 46 carries a needle 56, which controls flow through a passage 58, through a restriction 60, to a chamber 62. The movement of the diaphragm 46 to the right is resisted by the compression spring 63. The left-hand wall of chamber 62 is formed by a diaphragm 64. The diaphragm 64 carries a balance valve 66 and is pushed to the left to the open position by the

2

compression spring 96, which permits fuel to escape from the chamber 62, through the passage 68, to the passage 70. Chamber 72 is located on the left-hand side of the diaphragm 64 and is connected through the passage 74 to the chamber 54, and, therefore, to the fuel outlet 26.

When the fuel passes the venturi 44, it divides; a portion goes to the right through the passage 76, passes the valve 78, flows through the passage 80 and rejoins the other branch in the outlet 10. The other branch flows through 44, flows through the passage 82, passes the valve 84 and flows through the passage 86 and rejoins the fuel outlet at 10. The valve 84 is pushed to the right to the restricted position by an increase in temperature in the bulb 144. The fuel united in the passage 70 then passes the low-speed control valve 88, which is shown wide open, that is, in its inoperative position; fuel then flows to the chamber 90, the upper wall of which is formed by a diaphragm 92. A chamber 94, located above the diaphragm 92, communicates through a pipe 98 and a restriction 100 with the chamber 30 to the right of diaphragm 24. The diaphragm 92 carries a balance valve 104, and the diaphragm is pushed up by a compression spring 102. The fuel thus escapes through the pipe 106 and discharges through the outlet 108 into the air pipe 112, downstream of throttle 114. The mixture of fuel and air is then compressed in the engine-driven supercharger 120, which is driven by shaft 202. This mixture is discharged through the inlet manifold 140.

Air enters the pipe 112 to the left of the throttle valve 114, which throttle is connected through a link 116 with the low-speed control valve 88. A pipe 122 leads out of the supercharger outlet and is connected to a chamber 124. In the chamber 124 are evacuated elements 128, which control the movement of the valve 78. Coupled to these three elements 128 is the single element 130, which is responsive to the exhaust back pressure.

A temperature-responsive element 144 leads out of the supercharger outlet and is connected through a pipe 148 with the pressure responsive elements 150. The elements 150 are located in a chamber 152. This chamber 152 is connected through the passage 156 with the chamber 124. The two chambers 160 and 162 are also connected to the passage 156. These chambers 160-162 contain compression springs, which engage with the valves 78 and 84.

To the right of the venturi 44 is a chamber 164, which communicates with the throat of the venturi 44. This chamber contains a compres-

sion spring 166 and is located above a diaphragm 178. This diaphragm 178 forms the upper wall of a chamber 172, which communicates with the fuel line 26. A passage 174 is obstructed by a valve 176, carried by the diaphragm 178 and the compression spring 166 reduces the obstruction of valve 176. As the valve 176 rises, the obstruction increases. Passage 174 communicates with the passage 26 and through the obstruction 176 with the passage 180, which communicates with the port 182, controlled by the valve 184. In the position shown, which is the automatic rich (A. R.) position, the valve 184 closes the end of passage 180, that is, it closes the port 182. The port 186 in the valve 184, when the lever 188 is moved clockwise about 30° into the automatic lean (A. L.) position, permits a small flow through the passage 174, passage 180, port 182, port 200, port 186, into the passage 190 in the pipe 88, so that a certain quantity of fuel discharged by the pump 14 escapes through the passage 174 to the pipe 88 and back to the chamber 38, through the restriction 100 and past the valve 34 to the return passage 36. This flow raises the pressure in the chamber 34 and thus reduces the pressure drop past the restriction formed by valve 34 and 78. Hence the fuel flow is reduced. This is the automatic lean (A. L.) position.

If the lever 188 is moved about 90° clockwise from the A. R. position, the opening 200 no longer restricts the connection from passage 180 to passage 98. Hence, in this position, the Idle Cut Off (I. C. O.) position, full pressure is applied to the chamber 34, which acting on the diaphragm 92, cuts off all the fuel flow by closing the valve 104.

What I claim is:

1. Fuel supply means for an internal combustion engine having an air entrance leading to an inlet manifold comprising a fuel pump, a fuel outlet therefrom, a variable pressure-relief valve for said outlet, engine speed responsive means to regulate said variable pressure whereby as the speed increases the pressure in said outlet increases, two parallel passages leading from said pump to a variable restriction in each of said parallel passages, means responsive to the manifold air pressure and to the pressure in the exhaust manifold connected to one of the restrictions to move said variable restriction into the open position as the exhaust pressure decreases and as the manifold air pressure increases, temperature responsive means connected to the other variable restriction to close said other restriction as the temperature rises.

2. A device as set forth in claim 1 in which there are means responsive to the velocity of the fuel flowing towards said two parallel outlets adapted to admit additional fuel beyond said restrictions.

3. A device as set forth in claim 1 in which there is a valve and a pressure responsive diaphragm controlling said valve, said valve being located in the passage through which the fuel flows from said parallel fuel outlets, a diaphragm responsive to the pressure outlets created by said velocity device, a valve connected to said diaphragm, a fuel passage the flow through which is controlled by said valve, a manually controlled valve in said passage downstream from said diaphragm controlled valve, a restricted passage connecting said manually controlled valve with the fuel entrance, a chamber one wall of which is formed by said first mentioned diaphragm and a passage connecting said chamber to the manually controlled valve between said restriction and said valve.

4. Fuel supply means for an internal combustion engine having an air entrance leading to an inlet manifold comprising a fuel pump, a fuel outlet therefrom, a variable pressure-relief valve for said outlet, engine speed responsive means to regulate said variable pressure whereby as the speed increases the pressure in said outlet increases, two parallel passages leading from said pump to a variable restriction in each of said parallel passages, means responsive to the manifold air pressure connected to one of the restrictions to move said variable restriction into the open position as the exhaust pressure decreases and as the manifold air pressure increases, temperature responsive means connected to the other variable restriction to close said other restriction as the temperature rises.

5. A device as set forth in claim 4 in which there are means responsive to the velocity of the fuel flowing towards said two parallel outlets adapted to admit additional fuel beyond said restrictions.
